UNITED STATES PATENT OFFICE.

FREDERICK A. HART, OF NEWARK, NEW JERSEY, ASSIGNOR TO UNDERWOOD COMPUTING MACHINE COMPANY, OF NEW YORK, N. Y., A CORPORATION OF NEW YORK.

COMBINED TYPEWRITING AND COMPUTING MACHINE.

1,356,279.

Specification of Letters Patent. Patented Oct. 19, 1920.

Application filed February 5, 1916. Serial No. 76,269.

To all whom it may concern:

Be it known that I, FREDERICK A. HART, a citizen of the United States, residing in Newark, in the county of Essex and State of New Jersey, have invented certain new and useful Improvements in Combined Typewriting and Computing Machines, of which the following is a specification.

My invention relates to totalizers of typewriter computing machines, and more particularly to the manner of supporting, adjusting and detaching the totalizers. The improvement is herein illustrated as applied to a combined typewriting and computing machine wherein a typewriting machine somewhat analogous to the usual Underwood typewriting machine is employed. It is usually convenient in building a key-operated computing mechanism which is to be combined with such a machine, to include a totalizer which travels along step by step with the typewriter carriage. Where such a construction is employed, however, it is necessary to provide that the totalizer be brought exactly into position to aline with the master wheel which operates it. To obtain such a result, it has frequently been found necessary to provide a carriage for the computing mechanism separate from the typewriting mechanism, or else it has been found necessary in many cases to employ complex devices for locking or steadyng the totalizer while engaged with the master wheel. Both of these add to the weight of the moving parts, and to their number.

According to the present invention, the typewriting machine carriage may be made as a unit with a computing machine carriage, and the totalizer may be attached firmly to such a combined carriage, with the result that the whole machine is more rigidly held in position than hitherto considered advantageously possible, while at the same time, by a proper arrangement of the roller bearings for this combined carriage, it has been found possible to hold both the front and rear ends of said carriage alined, with the result that even though the usual Underwood carriage operation and escapement are employed at the back of the carriage, there

is, nevertheless, no observable tendency to twist the typewriter carriage.

It has been found possible to obtain a maximum efficiency of rectilinear travel for the front of the typewriter carriage by providing two sets of roller bearings at the front thereof, each set comprising widely-spaced pairs of rollers, with the result that the bearings for the front of the machine all maintain a practically rigid support for the totalizer, while the bearings at the rear of the machine may be similarly widely-spaced. The groups of rear rollers may be so arranged as to get a positive grip in every direction on the rear rail along which the carriage travels.

For the purpose of locating the totalizer or totalizers at the correct position with respect to the carriage, the front part of the carriage is formed or provided with a longitudinal bar, and this bar is provided with a longitudinal slot or channel in which fits a key in the form of a headed stud, whereby the totalizer is clamped to the bar. The totalizer is provided with guide tongues which fit in said slot or channel, one tongue on each side of the totalizer, whereby the same is held against canting. In the specific embodiment of this feature of my invention I have found it advantageous to provide both the totalizer and the front end of the carriage with a series of V-shaped teeth, so that the totalizer may be forced into position by the coöperation of said teeth, by merely turning an ordinary thumb-screw. To assist in adjusting the totalizer properly, by co-operating with the above-described teeth, I have found it advantageous to provide the totalizer with the lugs or guide tongues already referred to, which set into the channel and yet are slidable along said channel, with the result that by slackening the thumb-screw, the totalizer is released from its teeth and the totalizer is slidable along to any desired point on the carriage. To prevent the totalizer from accidentally becoming detached while being slid, the thumb-screw may hold the totalizer by means of the headed stud, which enters said channel, and the head of which overlaps into slots extending from said channel.

Other features and advantages will hereinafter appear.

In the accompanying drawings,

5 Figure 1 is a plan view of the forward portion of the machine.

Fig. 2 is a front elevation of Fig. 1, with some of the parts broken away.

Fig. 3 is a detailed plan view of the roller carrier, one end being broken away.

10 Fig. 4 is a side elevation of Fig. 1, some parts being broken away, so as to expose other parts.

Fig. 5 is a detailed perspective view, showing the totalizer secured to the carriage 15 rail.

Fig. 6 is a detailed sectional view of a portion of the totalizer, taken on the line 4-4 of Fig. 4, and looking in the direction of the arrow at said line.

20 Fig. 7 is a fragmentary sectional view taken on the line 2-2 of Fig. 2, looking in the direction of the arrow at said line.

Fig. 8 is a detail view of the totalizer mounting, and shows the totalizer held away 25 from the carriage, so that it can be moved lengthwise thereof.

The machine frame 8 has projecting upwardly therefrom standards 9 and 10. Brackets 11 are secured to the standards 9 30 at the ends of the typewriting machine and have secured thereto a front guide rail 12 by means of screws 12^a. A rear guide rail 13 is supported by the standards 10. The typewriter carriage comprises end bars 14 and 15 forming part of the carriage frame 16. The front member on bar 17 of the carriage extends downwardly and is secured to the frame 16 thereof by means of screws 18. The carriage is provided with the usual 40 rotatable platen 19, and is carried on and guided by pairs of rollers 20 and 21, which travel on tracks in the front rail 12 as will hereinafter be more fully described. At the rear the carriage is guided by groups of 45 three rollers each 22, 23, and 24, which are disposed near opposite ends of the carriage, so that the great distance between the points of support will give great resistance to twisting vibration of the carriage. This is 50 analogous to the structure disclosed in the patent to Barnard, No. 949,723.

A totalizer forming part of a computing mechanism 25, is mounted on the front bar 17 of the typewriter carriage and is provided with register wheels 26, which are caused to be operated, in the usual way, through intermediate gears 27, by a master wheel 28 journaled in a casing 30; said casing being secured to the machine frame.

60 The totalizer 25 comprises a front casing 31 provided with a sight opening 32, side plates 33 and 34 and a rear plate 35. To lock the totalizer to the carriage bar, there is provided a headed stud 46 which enters 65 the bar 17 and is adapted to draw the total-

izer 25 against said bar 17. To operate this stud 46, a bell-crank 36 provided with arms 37 and 38, is loosely mounted on a rod 40 forming part of the totalizer, said bell-crank held in position lengthwise thereof 70 by sleeves 41 and 42. The arm 37 of the bell-crank projects into a hole 43 formed in the rear plate 35 of the totalizer, where it is engaged by a thumb-screw 44 threaded into the rear plate 35. The arm 38 of the 75 bell-crank operates the stud 46, and for this purpose said arm 38 is received in a slot 45 in the stud 46. The plunger or stud is provided with a head 47, which may be drawn against the inner side of flanges 48 formed 80 on the front carriage bar 17. The rear plate 35 is provided with sets of teeth 51, 52, (see Fig. 5), which engage serrated supports 53 and 54 formed on the front rail of the carriage. The rear plate 35 is also provided with projections 55 which extend into a T-slot 56 formed in the front bar 17 by the flanges 48.

To attach the totalizer to the carriage, the screw 44 is raised, allowing the stud or plunger 46 to be moved outwardly from the rear plate 35 of the totalizer by the spring 50 coiled about the rod 40, which tends to normally hold it outward. If the totalizer is now set on the carriage bar 17 from 90 either end thereof, the parts will bear the relation to each other as shown in Fig. 8, in which the head 47 of the plunger 46 is shown inserted in the slot 56 and behind the flanges 48. In this position, steadyng projections 55 fast to the totalizer extend partly into the slot 56 formed in the bar 17. In this position, the totalizer can be moved lengthwise of the carriage and adjusted to the proper columnar position. The screw 105 44 then may be manipulated to swing the lever 36 and cause the plunger 46 to draw the totalizer tightly against the front bar 17. This forces the totalizer into place by forcing V-shaped serrated teeth 51, 52, on 110 the totalizer, to engage with and seat themselves solidly in corresponding teeth or serrated supports 53 and 54 on the carriage bar 17. Since these teeth are advantageously at letter-space intervals, they both 115 firmly support and aline the totalizer at the proper position relative to the master wheel 28. The teeth 51 and 52 do not ordinarily engage with the teeth 53 and 54 unless the screw 44 is tightened, because the spring 50 120 holds the totalizer clear of the teeth 53, 54.

In order to get the best possible effect, the row of teeth 51 is at the top edge of the totalizer, while the row of teeth 52 is near the bottom of the totalizer, and the rows of 125 teeth 53, 54, which coöperate with them, are located at corresponding heights on the bar 17.

The rollers 20 and 21 are rotatably mounted in slots 57 and 58, respectively, in a frame 130

or cage 60. There are two such roller carriers 60 in each raceway 61, which are loosely pivoted to a spacing frame 62 at 63 and 64. This frame 62 comprises two plates 5 or bars 65 firmly secured to each other by rivets 66 and held apart from each other by spacers or washers 67. To keep the rollers 20 and 21 properly located, the spacing frame has journaled thereon a pinion 68 on 10 a short shaft 68' between the bars 65, which meshes with each of the racks 70 and 71; the rack 70 being carried by the front guide rail 12 on the frame of the machine, and the rack 71 being carried by the front carriage 15 bar 17. The racks 70 and 71 are held in slots 73 and held in place by projections 74 which fit tightly in holes 75. It will be seen that while the carriage is being moved from side to side of the machine, the spacing 20 frame will be driven by its pinion 68, so that the rollers will move half the distance of the travel of the carriage, because the pinion meshes on one side with the fixed rack 70 and on the other with the driving rack 71. 25 The frame 16 of the typewriter carriage is secured to the side bars 14 and 15 by means of screws 76 and 77 respectively, and comprises cross bars 78 and 79 joined together by arms 81. 30 A bar 82 supported by the standards 9 is provided with the usual scale 83 with which the usual pointer 84 co-acts to indicate the position of the typewriter carriage, the pointer, however, curling up from the carriage 35 over the scale 83.

It will be noted that the rail 13 against which the rollers 22, 23, and 24 bear, is at the extreme rear of the machine, and that, as disclosed in said Barnard patent, there 40 are two sets of three rollers each, the sets being near the opposite ends of the typewriter carriage. Since each group of three rollers is arranged to bear substantially at the corners of an equilateral triangle inscribed in the rail 13, said rollers prohibit any vibration at the rear of the typewriting machine.

For the purpose of giving great steadiness to the front of the typewriter carriage and 50 the totalizer, each roller 21 stands at right angles to its roller 20, and the tracks 85 on which the rollers 21 run are set at right angles to the tracks 86 on which the rollers 20 run, and these tracks 85 and 86 are set at 55 an angle of 45 degrees with the horizontal. To afford additional steadiness to the carriage of the combined typewriting and adding machine, there are two sets of tracks 85 and 86, one adjacent the bottom of the bar 60 17, and the other adjacent the top thereof, so that one set of tracks is nearly at the top of the totalizer and the other nearly at the bottom. This gives great steadiness to the front of the typewriter carriage, and consequently 65 to the totalizer 25.

In order to avoid binding, there is provided for the top sets of rollers 21 and 20, a carrier or spacing frame 62 and pinion 68 entirely separated from the carrier for the other set of rollers. 70

Variations may be resorted to within the scope of the invention, and portions of the improvements may be used without others.

Having thus described the invention, I claim:

4. In a combined typewriting and computing machine, the combination with a totalizer having a series of V-shaped teeth at letter-space intervals, of a traveling carriage having a series of V-shaped teeth at letter-space intervals, means including a lug on said totalizer engaging in a slot in said carriage for maintaining said totalizer with its series of teeth opposite the series on said carriage, and means for moving said totalizer into position to cause its teeth to engage with those of the carriage, thereby positioning said totalizer correctly with respect to a letter-space position on said carriage. 80

2. In a typewriting and computing machine, the combination of a typewriter carriage comprising flanges, a totalizer, means for rigidly securing the totalizer on the typewriter carriage, said means comprising a thumb screw, coöperating teeth on said totalizer and carriage, and a carriage-engaging member operated by said screw which coöperates with flanges on the typewriter carriage. 90

3. In a combined typewriting and computing machine, the combination of a totalizer provided with a series of V-shaped teeth at letter-space intervals, of a traveling carriage, a series of V-shaped teeth at letter-space intervals on said carriage, slidable 100 means to maintain said totalizer with its series of teeth opposite that on said carriage, and means to hold said totalizer away from said carriage to prevent coöperative engagement between the two series of teeth, 105 and thereby enable movement of said totalizer along said carriage. 110

4. In a combined typewriting and computing machine, the combination of a totalizer provided with V-shaped teeth, a typewriter carriage, serrated supports for said totalizer on said carriage, whereby said totalizer is properly positioned on said carriage, means for holding the teeth on the totalizer out of coöperative engagement with the serrated supports, and means for guiding the totalizer while it is being moved lengthwise of the carriage during an adjustment operation. 120

5. In a combined typewriting and computing machine, the combination with a totalizer, of means for supporting and guiding the same, comprising a traveling bar along which said totalizer may be secured in adjusted position, said bar being pro- 125 130

- vided with a V-groove, a stationary bar having a complementary V-groove, two roller bearing devices in the runway formed by said grooves, each of said devices comprising two rollers and a roller frame for supporting the same in proper relative position, a connecting frame pivoted to both of the roller frames, a pinion supported on said connecting frame, and racks with which 5 said pinion coöperates, said racks being at the bottoms of said grooves in the traveling bar and stationary bar, respectively.
6. In a combined typewriting and computing machine, the combination with a 10 totalizer, of supporting and guiding means therefor, comprising a traveling bar having a V-groove, means to hold said totalizer in adjusted position on said traveling bar, a stationary bar having a complementary V- 15 groove, anti-friction members in said grooves, each of said anti-friction members comprising rollers and a frame for holding said rollers in proper relative position, a spacing member pivoted to each of said 20 frames and connecting the same, a rack positioned in a slot at the bottom of each V-groove, and a pinion pivoted on said connecting member and meshing with both of 25 said racks.
- 30 7. In a combined typewriting and computing machine, the combination with a traveling carriage, of a bar at the front end of said carriage, sets of teeth on said bar, a totalizer adjustable along said bar and comprising a set of teeth near the upper end 35 thereof adapted to coöperate with teeth on the carriage, a second set of teeth on said totalizer near the lower end thereof adapted to coöperate with teeth on said carriage, 40 and a headed locking member entering a T-shaped groove in said bar adapted to lock said totalizer to said carriage.
8. In a combined typewriting and computing machine, the combination with a 45 traveling carriage, of a bar at the front end of said carriage, sets of teeth on said bar, a totalizer adjustable along said bar and comprising a set of teeth near the upper end 50 thereof adapted to coöperate with teeth on the carriage, a second set of teeth on said totalizer near the lower end thereof adapted to coöperate with teeth on said carriage, a headed locking member entering a T-shaped groove in said bar adapted to lock 55 said totalizer to said carriage, and a lug forming a part of said totalizer coöperating with said groove to hold the totalizer horizontally alined.
9. In a combined typewriting and computing machine, the combination with a 60 traveling carriage, of a bar at the front end of said carriage, sets of teeth on said bar, a totalizer adjustable along said bar and comprising a set of teeth near the upper 65 end thereof adapted to coöperate with teeth on the carriage, a second set of teeth on said totalizer near the lower end thereof adapted to coöperate with teeth on said carriage, a headed locking member entering a T-shaped groove in said bar adapted to lock said totalizer to said carriage, and a lug forming a part of said totalizer coöperating with said groove to hold the totalizer horizontally alined.
10. In a combined typewriting and computing machine, the combination with a traveling carriage, of a bar at the front end of said carriage, sets of teeth on said bar, a totalizer adjustable along said bar and comprising a set of teeth near the upper end 70 thereof adapted to coöperate with teeth on the carriage, a second set of teeth on said totalizer near the lower end thereof adapted to coöperate with teeth on said carriage, a headed locking member entering a T-shaped 75 groove in said bar adapted to lock said totalizer to said carriage, a lug forming a part of said totalizer coöperating with said groove to hold the totalizer horizontally alined, and means for normally holding said totalizer teeth clear of the carriage teeth, whereby the totalizer may slide along the carriage.
11. In a combined typewriting and computing machine, the combination with a 80 traveling carriage, of a totalizer, means for supporting said totalizer on said carriage for sliding movement therealong, and for holding said totalizer out of engagement with said carriage, means to force said totalizer into engagement with said carriage, and coöoperating devices on said totalizer and said carriage, whereby said totalizer will be correctly positioned in a predetermined letter-space position during the movement of said totalizer into engagement with said carriage.
12. In a combined typewriting and computing machine, the combination with a typewriter carriage including flanges, of a totalizer, means for firmly securing the totalizer on the typewriter carriage, said means including a thumb-screw, and a carriage-engaging member coöperating with said flanges on the typewriter carriage and operated by said thumb-screw.
13. In a combined typewriting and computing machine, the combination with a totalizer, of supporting and guiding means therefor, comprising a traveling platen-carriage supported at the rear of the machine, and including a front bar by means of which said carriage is supported at the front of the machine, means to secure said totalizer in adjusted letter-space position on said front bar, said front bar having V-grooves near its opposite edges and facing in opposite directions, a stationary bar having V-grooves complementary to those of said front bar, two roller-bearing devices in each run- 125

- way formed by said grooves, each of said devices comprising two rollers and a roller-frame for maintaining the same in proper relative position, a connecting frame pivoted to both of the roller frames, a rack positioned in a slot at the bottom of each groove, means to prevent longitudinal movement of each rack in the corresponding groove, and a pinion pivoted on each connecting frame and engaging with the racks in the grooves, comprising the runway in which the connecting frame lies.
14. The combination with a support having a longitudinal channel therein, of a totalizer adjustable along said support, a pair of spaced lugs at the ends of the back of said totalizer extending into said channel to prevent a turning movement of said totalizer relative to said support, a device for holding said lugs in said channel to permit the totalizer to slide while held by said lugs, and locking means for securing said totalizer on said support and forming an extension of said device.
15. The combination with a support having a channel extending longitudinally thereof, of a totalizer adjustable along said support, meshing teeth on said support and said totalizer, preventing relative longitudinal movements, lugs on said totalizer engaging said channel, preventing vertical and
- turning movements, and a clamp engaging in said channel adapted to support said totalizer free of said support teeth, and adapted to be set to prevent spreading movements 35 of said totalizer with respect to said support.
16. The combination with a bar comprising a longitudinal channel, of a totalizer adjustably mounted on said bar and including a lug slideable along said channel, a lock of which said lug forms a part adapted to draw said totalizer against the bar, and means for drawing on said lug adapted to positively hold it against release by pressure 40 exerted on the totalizer.
17. The combination with a bar comprising a longitudinal channel, of a totalizer adjustably mounted on said bar and including a lug slideable along said channel, a lock 45 of which said lug forms a part adapted to positively draw said totalizer against the bar, and to support it when clear of the bar to permit it to be shifted therealong, and means for drawing on said lug, adapted to positively hold it against release by pressure 50 exerted on the totalizer.
